Primary Examiner — Mary Ann Calabrese*Assistant Examiner* — Katelin G Kloberg(74) *Attorney, Agent, or Firm* — Patent Negotiator, PLLC; Sarita L. Pickett(57) **CLAIM**

The ornamental design for a carpenter's accordion as shown and described.

DESCRIPTION

FIG. 1 is a front elevation view of a carpenter's accordion, showing my new design;

FIG. 2 is a left elevation view thereof;

FIG. 3 is a bottom view thereof;

FIG. 4 is a rear elevation view thereof;

FIG. 5 is a top view thereof;

FIG. 6 is a right elevation view; and,

FIG. 7 is a bottom-front-right perspective view thereof.

Wherein objects of the environment illustrated in broken lines form no part of the claimed design.
